Joseph J. O'Brien

ATTORNEY.

UNITED STATES PATENT OFFICE.

JOHN HEALD, OF SPRINGFIELD, MASSACHUSETTS.

CONCERT HORN.

Application filed June 13, 1923. Serial No. 645,193.

This invention relates to improvements in concert horns and one of its leading objects is to provide a horn of this type with means whereby the tone may be muffled or modified 5 by directing the bell of the horn against the side of the body of the player.

With the above and other objects in view, the invention relates to certain new and useful improvements, constructions, combinations and arrangements of parts, clearly described in the following specification, and fully illustrated in the accompanying drawing, in which:

Fig. 1 is a front elevation showing the bell of the horn in perspective.

Fig. 2 is a transverse sectional view taken on line 2 looking in the direction of the arrow.

Fig. 3 is a side elevation of a detail showing the means for changing the key of the horn, by shortening the air passage thereof.

Fig. 4 is a horizontal cross section of Fig. 3.

Referring to the accompanying drawings, 25 5 designates the mouth-piece of the instrument which is detachably mounted in the usual manner on the intake pipe 6 which communicates by various passages with the tapered horn pipe 7, which carries the bell 30 8 which forms an outlet for the instrument.

In Fig. 1, I show one arrangement of the connections between the intake pipe 6 and the horn pipe 7. The upper portion of the intake pipe 6 is shown to be disposed in a 35 horizontal plane and to have connection with the right angular downwardly directed branch 9 which communicates by a detachable U-shaped union on the branch 10 with the downwardly facing leg 11 of a U-shaped 40 switch branch 12. The other leg of the U-shaped switch branch 12 is adapted to be connected at 13 with one leg of the extension 14, the other leg of which is connected at 15 with the short branch leading to the 45 valve chamber in the lower end of the valve casing 16. The valve casing 16 communicates with the valve casing 17 through the by-pass 18. A U-shaped half note branch 19 is connected at its ends with the casing 50 17. The casing 17 communicates with the valve casing 20 by means of the by-pass 21. A full note branch 22 is connected at its upper end with one portion of the valve casing 20 and at its lower end with another portion 55 of said valve casing. Valves controlled by finger pressed keys 23 work in said valve

casings to control the flow of air in the different passages in accordance with old and well-known practice. The valve casing 20 has an outlet at 24 with the U-shaped branch 25 and its opposite leg 26 extended upwardly and connected at 27 with the downwardly directed leg of the tapered horn pipe 7 leading to the bell 8. The various parts of the instrument here described are suitably braced with each other in accordance with standard practice, such details forming no part of this invention.

The union 10 is provided with a drain nipple 10^a which is controlled by means of a lever valve 10^b of the lug 10^c carried by said member 10 in accordance with the usual practice. The extension member of the branch 14 is provided with detachable sections 14^a or 14^b whereby the instrument may 75 be adapted to play in B flat. By removing the extensions the instrument will play in C, when the terminals of the U-shaped member 14 are connected as shown in Fig. 1. By removing the member 14 entirely and connecting the leg 10^d of the union 10 with the branch 15 the instrument will play in E flat, the inverted U-shaped union 12 being thus cut out from the air circulation system of the instrument.

The tapered end 8^a of the bell 8 is provided with a reduced portion 8^b which is inserted in the socket 7^a of the horn pipe 7 so that said bell 8 can be swivelled into any desired angular position in a complete circle 90 of its movement on the socket 7^a. The socket 7^a is provided with a clamping ring 7^b controlled by the wing nut 7^c so that the the horn can be held in any desired adjusted position. It will be observed that the instrument is designed so that the bell is supported in a plane considerably below the mouth-piece 5 so as to not interfere with the vision or comfort of the player. This construction is such that the bell is supported so as to occupy a position adjacent the side of the player when the instrument is being used and this arrangement permits the player to place the mouth of the bell against his side so as to regulate the velocity 100 and volume of the air moving through the horn by placing the mouth of the horn against his side. In this way by skillful adjustment of the horn against the side of the player he may muffle the tone to produce a 105 muting action at will, without in any way requiring a modification of the technique of

the playing. By means of the swivelled connection between the bell and the horn pipe this muting action can be controlled to suit the convenience of the player or his sitting or standing position or the bell can be adjusted to an angular position facing away from the player to permit of the discharge of the full volume of the tone without any muting, and the direction of such discharge can be controlled at will so as to face forwardly or rearwardly or to either side of the player.

Having described my invention, I claim:

1. A musical horn comprising a mouth-piece, a bell, passages providing communication between the bell and mouthpiece and valves controlling said passages, the bell being located at one end of the instrument and the mouth-piece at the other end and the bell facing laterally of the axis of the instrument to permit the player to press the same against his side to mute the tones produced in playing the instrument.
2. A musical horn comprising an instrument having a series of valve controlled passages and a mouth-piece at one end of the instrument for said passages and a bell

at the opposite end of the instrument, the bell having swiveled connection with the instrument and being disposed laterally of the axis of the instrument to engage the side of the player to permit of a muting action.

3. A musical horn comprising an instrument having a pipe at one end of which is a mouth piece and at the opposite end of which is a bell, the bell being disposed below the mouth piece in normal playing position and being adapted to be moved against the body of the player to permit the player to mute the sounds produced in the instrument.

4. A musical horn consisting of a pipe provided with a mouth piece at one end and a horn at the opposite end, such pipe being provided with plungers and different passages and valves controlling said passages, the bell being located below the valves and mouth piece and an adjustable connection between the bell and the pipe whereby the bell may be moved to muting engagement with the body of the player or out of said engagement.

Signed by me at Springfield, Mass.

JOHN HEALD.
